(57) **CLAIM**

The ornamental design for a bottle, as shown and described.

DESCRIPTION

FIG. 1 is a top perspective view of the bottle, showing my new design;

FIG. 2 is a front view of the design illustrated in FIG. 1, the rear, left side, and right side views being identical thereto; FIG. 3 is a top view of the design illustrated in FIG. 1; and, FIG. 4 is a bottom top view of the design illustrated in FIG. 1. The broken lines in the drawings are for the purpose of illustrating unclaimed portions of the bottle and form no part of the claimed design.

1 Claim, 3 Drawing Sheets(56)
